UNITED STATES PATENT OFFICE.

LINCOLN KUENEMANN, OF RAMAPO, ASSIGNOR TO WILLIAM I. WALTER, OF NEW YORK, N. Y.

DESIGN FOR A PATTERN FOR PRINTED FABRICS.

SPECIFICATION forming part of Design No. 24,094, dated March 12, 1895.

Application filed January 9, 1895. Serial No. 534,384. Term of patent 3½ years.

To all whom it may concern:

Be it known that I, LINCOLN KUENEMANN, a subject of the Queen of Great Britain, residing at Ramapo, in the county of Rockland 5 and State of New York, have invented and produced a new and original Design for a Pattern for Printed Fabrics, (Case A,) of which the following is a specification.

The leading features of my design consist 10 in alternated lines formed by the parallel rows of staggered dots and the intermediate row of superposed X shaped figures.

In the drawing forming part of this specification, the design for the pattern is shown 15 consisting of a row of superposed X shaped figures, and an adjacent row of superposed

dots, the dots being formed into two lines, the dots of one line lying opposite the space between two dots of the other line. The rows of X shaped figures and dots alternate as shown.

I claim—

The design for a pattern for a printed fabric, substantially as herein shown and described. 25

Signed at the city, county, and State of New York, this 3d day of January, 1895.

LINCOLN KUENEMANN.
